UNITED STATES PATENT OFFICE.

JOSEPH D. SIMPSON AND WILLIAM G. TOPLIS, OF PHILADELPHIA,
PENNSYLVANIA.

DESIGN FOR A CLOTHES-LINE FASTENER.

SPECIFICATION forming part of Design No. 24,212, dated April 16, 1895.

Application filed March 1, 1895. Serial No. 540,233. Term of patent 7 years.

To all whom it may concern:

Be it known that we, JOSEPH D. SIMPSON and WILLIAM G. TOPLIS, citizens of the United States, residing in the city and county of Philadelphia, State of Pennsylvania, have invented and produced a new and original Design for Clothes and other Line Fasteners, of which the following is a specification, reference being had to the accompanying drawings, forming part thereof.

The leading features of our design for a clothes and other line fastener, are, first, converging jaws with rounded surfaces; next, a jaw with a rounding face and inclined sides, and, finally, the attaching plate with a boss with which the inner end of one of the jaws is connected.

Figure 1 represents a perspective view of a line fastener embodying our design. Fig. 2 represents a transverse section thereof.

Similar letters of reference indicate corresponding parts in the two figures.

In the drawings, A designates the attaching plate, on the face of which is the boss B. Projecting forwardly from said boss is the lower jaw C, whose upper face D is rounded in cross section, and whose sides E are inclined or converging.

F designates the upper jaw, which joins the jaw C by the bend G, and whose lower face H is rounded in cross section.

Between the jaws is the tapering throat J, which is formed by the converging faces of the jaws in the longitudinal direction thereof.

What we claim is—
The design for a line fastener, substantially as described and shown.

JOSEPH D. SIMPSON,
WILLIAM G. TOPLIS.
